RAILWAY CAR CONSTRUCTION

Robert A. Meldrum, Alexandria, Va.

Application March 19, 1948, Serial No. 15,761

2 Claims. (Cl. 105—416)

1

This invention relates to railway car construction and more particularly to the central longitudinal framing member thereof commonly known as the center sill, the invention having for its principal object to provide a construction which is simple in design, stronger in effect, and more efficient in use than those heretofore proposed.

A further object of the invention is to provide as a center sill an improved cylindrical pressure vessel comprising a single chamber or one divided to provide a plurality of compartments, in place of the usual rolled structural or fabricated members heretofore proposed in the underframing for a railway car, the said cylindrical vessel serving as a column for the absorption of impact forces and butting loads commonly encountered in the operation of railway cars.

Another object is to utilize the said cylindrical vessel for the storage of liquids and/or gases used in connection with the operation of, and/or the servicing of, railway cars.

Another object is to simplify the fabrication and construction as well as the framing of railway cars with a considerable reduction in the dead weight of a car, and to concentrate the dead weight of liquids stored in the said cylindrical vessel on the longitudinal center line at the lowest possible elevation of the car in order to lower its center of gravity and to facilitate equilibrium and balance thereof.

A still further object of the invention is to provide for the complete cleaning and sterilization of the interior of the cylindrical pressure vessel.

With these and other objects in view as will become apparent from the following detailed description, the invention resides in the novel details of construction and combinations of parts as will be particularly pointed out and covered by the claims.

Referring to the accompanying drawings forming a part of this specification and in which like numerals designate like parts in all the views—

Fig. 1 is a horizontal plan view, partly in section, of the cylindrical pressure vessel constituting the center sill of a railway car;

Fig. 2 is a vertical transverse sectional view taken as on the line 2—2 of Fig. 1 and looking in the direction of the arrows;

Fig. 3 is a vertical transverse sectional view taken as on the line 3—3 of Fig. 1 and looking in the direction of the arrows;

Fig. 4 is an enlarged vertical sectional view of

2

the cylindrical pressure vessel to illustrate a joint between two cylindrical sections thereof as well as to show the division of the vessel as a whole into two adjoining compartments;

5 Fig. 5 is a horizontal plan view illustrating the joint between one end of the cylindrical pressure vessel serving as the center sill of the railway car, and the draft sill at one end of said car;

Fig. 6 is a side elevational view of the parts

10 illustrated in Fig. 5;

Fig. 7 is a vertical transverse sectional view of the draft sill, said view being taken as on the line 7—7 of Fig. 6 and looking in the direction of the arrows;

15 Fig. 8 is a vertical transverse sectional view taken as on the line 8—8 of Fig. 6 and looking in the direction of the arrows;

Fig. 9 is a vertical transverse sectional view through the cylindrical pressure vessel to show its relationship with a transversely disposed crossbearer or truss constituting a part of the underframing of the car;

20 Fig. 10 is a vertical sectional view taken as on the line 10—10 of Fig. 9 and looking in the direction of the arrows, to better illustrate the connection between said cylindrical vessel and said crossbearer;

Fig. 11 is a horizontal sectional view of the parts shown in Fig. 10, said view being taken as on the line 11—11 thereof and looking in the direction of the arrows; and

25 Fig. 12 is an enlarged detailed sectional view to illustrate the end constructions of the draft sill and the cylindrical pressure vessel, to form the joint therebetween.

30 In railway car construction there is provided a centrally disposed longitudinally extending center sill aligned with the draft sills at opposite ends of the car, together with transversely disposed spaced crossbearers, constituting the underframing of the car, but such center sills have conventionally comprised rolled or fabricated steel structural members the total weight of which has been very great, and the center of gravity as represented by the longitudinal center line of the center sill has been relatively close to the car floor and hence well above the horizontal plane of the top surfaces of the tracks or rails upon which the car rolls. By this invention there

40 is provided a center sill of hollow cylindrical construction of relatively large diameter, said center sill as a whole designed to have a total weight much less than the total weight of the present center sill made of rolled or fabricated structural members, as well as designed to have a struc-

55

tural strength much greater than the present rolled or fabricated center sill, and further designed so that its center of gravity is much nearer to the horizontal plane of the tracks.

Further, in heretofore known car constructions the storage tanks for liquids of necessity have been located to one side and/or the other of and parallel to the center sill thereby creating an unbalanced condition of the car, the size of such tanks being governed by such lateral disposition thereof, to the end that a limited quantity of liquid may be transported, necessitating relatively frequent fillings of the tanks. By this invention the cylindrical center sill is utilized as a storage tank for the necessary liquids incident to the operation of the car and, because said cylindrical center sill extends from draft sill to draft sill (nearly the entire length of the car) and has a relatively great diameter, said center sill has a relatively enormous liquid capacity whereby the car may travel longer and/or farther between fillings with liquid, or a car equipped with this type of center sill with such increased capacity may be provided with additional toilets, showers, or other devices requiring liquids such as water. Provisions are made for draining, cleaning and/or sterilizing the interior of this combined center sill and liquid storage tank.

The center sill comprises a hollow cylinder 2 which may be formed as a unitary member or as a plurality of aligned sections as indicated by the numerals 3 and 4 in Fig. 4, in the latter case the joint between the contiguous ends of the sections being welded as indicated at 5, and if additional strength is deemed necessary at such welded joint there may be provided one or more arcuate reinforcing plates such as 6 and 7 covering said joint and suitably secured as by welding to the cylindrical sections, edge fillet welds being preferred since they form a means of securing which is not only strong but which may be made or effected externally of the sections.

Each far end of the cylinder is provided with a closure member 10 which is preferably dished or arcuately formed and having a peripheral flange 11 adapted to closely engage the inner surface of the cylinder and secured thereto in liquid-tight relation as by welding, said closure member having its concave surface outermost for a purpose to be disclosed later. Said cylinder is fitted externally at each crossbearer with a pair of plates 12 and 13 constituting external stiffeners, and also fitted internally with an internal vertical reinforcing plate 14 which performs the function of a baffle to withstand and counteract movement of the contained liquid longitudinally of the tank or cylinder, said baffle extending from side to side of the cylinder but having a vertical dimension which is less than the internal diameter of the cylinder so as to provide a top opening 15 and the bottom opening 16 as clearly indicated in Figs. 2 and 3. Prior to insertion of said baffle in the cylinder, its arcuate side edges are rigidly secured as by welding to arcuate flange-like plates such as 17 and 18 and then the assemblage is slid into said cylinder, the flange-like plates contactingly fitting and subsequently secured to the inner surface of the cylinder as by the externally applied plug welds indicated at 19.

The vertical external stiffeners have their upper edge portions secured to and between the structural members such as the angle bars 25 and 26 of the top chord of the truss constituting the crossbearer, and have their lower edge por-

tions secured to and between the structural members such as the angle bars 27 and 28 of the bottom of said truss. The vertical outer edges of said stiffeners are reinforced by the flange plates 29 and 30 which are intercostal with respect to the top and bottom structural members of said truss. Cover plates 31 and 32 may be provided respectively at the top and bottom of the truss and extending from side to side of the car, to cover the space between respectively the top pair of angle bars 25 and 26, and the bottom pair of angle bars 27 and 28, see Fig. 10. The construction of internal and external stiffeners, as just described, is repeated at each crossbearer which are spaced from each other longitudinally of the car as desired or found necessary.

Within the cylindrical pressure vessel constituting the tank and preferably along the axis thereof, there is provided a perforated cleaning or scavenging pipe 35 passing through and secured to the plurality of baffle plates such as 14, said pipe being supplied with steam or other fluid scavenging medium from a suitable source in the direction of the arrow in Fig. 1 through the valved inlet pipe 36. Below this pipe and substantially in the vertical plane thereof and also passing through and rigidly secured to said baffles, is an imperforate pipe 37 for conducting (for example) a heating medium (steam) from any suitable source through the valved inlet pipe 38 to and through said pipe 37, to be discharged through the outlet pipe 39 as indicated by the arrows in said Fig. 1, the normal purpose of such a heating pipe being to prevent the liquid in the tank from freezing or reaching too low a temperature for its intended use. Therefore and broadly, the pipe 37 may be stated as a means for maintaining a temperature range for the desired supply of liquid (fluid) in the cylindrical tank, it being conceivable that said range might be above or below the freezing point of the fluid according to the intended use of the fluid in the car. The complete fluid temperature control circuit, with its necessary and well known electrical and/or mechanical control valves, is not illustrated in the interest of simplicity of the drawings, and since it is well understood in the art.

When the center sill is intended to comprise two or more tank sections, a partition 40 is provided as indicated in Fig. 4, said partition preferably being arcuately formed as illustrated for strength, said partition being a substantial duplicate of the end closure member 10 heretofore described. When the cylindrical tank is formed of a plurality of aligned sections such as 3 and 4, there may be provided an internal reinforcing ring or plate 41 at the joint between the sections also as indicated in Fig. 4.

A bottom cover plate 42 is preferably provided under the car and secured to the crossbearers as indicated in Fig. 10 and, if desired, a layer of fibrous or other insulation 43 may internally line said cover plate. The bottom members of each truss constituting a crossbearer, are preferably arcuately formed as indicated in Fig. 9 and have their ends curved or otherwise upwardly extended to join the ends of the top chord of the truss, each truss being suitably secured to the opposite side sills 44 and 45 which extend longitudinally of the car, the top framing members of the car being indicated at 46 and 47. Thus it will be seen that the entire outer surface of the car may be smoothly formed in the interest of streamlining, all the rest of the apparatus and equipment incident to the operation of the car being mounted

under the car floor and protected by the bottom cover plate 42 with suitable openings through said cover plate to provide access to the operating valves and controls for said operating apparatus and equipment.

With particular reference to Figs. 5 and 6, 7, 8 and 12 there is illustrated the connection between the cylindrical pressure vessel 2 constituting the center sill, and the draft sill 50 at one end of the car, it being understood that a similar connection will be provided with respect to the draft sill at the other end of the car. The draft sill throughout the major portion of its length generally may have the conventional shape and formation as now provided and comprising the box-like or rectangular cross-sectional shape as indicated in Fig. 7, there being indicated in dot-and-dash representation the location of a car wheel 51 contacting the top surface of a rail 52, said car wheel being the innermost wheel of the usual truck upon which the car is pivotally mounted. In other words, the draft sill is of a length at least equal to the overall length of the truck.

The innermost end of the draft sill terminates approximately at the innermost end of the truck, and is enlarged and circularly formed to provide a tubular end portion 53 the extreme edge portion of which is inwardly reduced in diameter as indicated at 54 in Fig. 12 for telescopically engaging and fitting the inner surface 55 of the end of the tank section, the closure member 10 for said tank being recessed inwardly to accommodate the end 54 of the draft sill. The formation of the innermost end of the draft sill is such that the horizontal plane of the top surface of the rectangular portion thereof is substantially tangent to the upper curved portion of the enlarged cylindrical end, and the lower curved portion of said end is tangent to a plane (horizontal) disposed materially below the plane of the bottom surface of the rectangular portion of said draft sill. Chamfers 56 and 57 are provided respectively on the draft sill and tank section so that when the two are interfitted there will be a V-shaped groove for receiving welding material indicated at 58 in Fig. 6 for uniting the two structures into a unitary whole. A suitable valved drain 59 is provided on the tank for use in connection with the scavenging thereof, and exterior arcuate plates 60 and 61 may be provided for covering the joint between the draft sill and the center sill.

Should additional liquid and/or gas storage be desired, auxiliary tanks may be provided therefor at any convenient or suitable location, which tanks would be supported by crossbearers in manners the same as or similar to the support of the center sill cylindrical tank, and in accordance with structural practice and/or requirements. Further it is conceivable that certain contained liquids and/or gases would have corrosive effect upon the inner surface of a tank, and hence this invention is intended to cover a tank construction either with or without a suitable anti-corrosive lining or treatment.

It will be understood that the fluid, such as water, may be charged into and withdrawn from the tank by any suitable means, there being illustrated in Fig. 6 the relatively large inlet pipe 70 and the outlet pipe 71, the latter (which may be one of many dependent upon the services for the liquid in the car) obviously extending downward

to terminate near the bottom of said tank. Also a third pipe 72 is shown serving as a means for supplying air under pressure to assist in the liquid withdrawal.

It is obvious that those skilled in the art may vary the details of construction and arrangements of parts without departing from the spirit of this invention, wherefore it is desired not to be limited to the exact foregoing disclosure except as may be required by the claims.

What is claimed is:

1. In railway car construction, the combination of a draft sill and an underframing, said underframing including a center sill comprising a hollow structure of curviform cross section, said structure provided with a fluid tight closure member in each end portion thereof, said structure constituting a storage tank for containing a fluid for use in said car, said draft sill being generally rectangular in transverse section throughout the major portion of its length and having a certain transverse area, the geometric centerline of said draft sill being displaced above and in substantially the same vertical plane with the geometric centerline of said center sill, said draft sill having its inner end deformed for complementary engagement with and rigid securement to an end of said center sill, said center sill having a transverse area which is materially greater than the said certain transverse area of said draft sill.

2. In railway car construction, the combination of a draft sill and an underframing, said underframing including a center sill comprising a hollow cylindrical structure provided with a fluid tight closure member in each end portion thereof, said structure constituting a storage tank for containing a fluid for use in said car, said draft sill being generally rectangular in transverse section throughout the major portion of its length, the geometric centerline of said draft sill being displaced above and in substantially the same vertical plane with the geometric centerline of said center sill, said draft sill having its inner end enlarged and circularly formed for complementary engagement with and rigid securement to an end of said center sill, the horizontal plane of the top surface of the rectangular portion of said draft sill being substantially tangent to the upper curved portion of the enlarged end of said draft sill, the lower curved portion of said end being tangent to a horizontal plane disposed materially below the plane of the bottom surface of the rectangular portion of said draft sill.

ROBERT A. MELDRUM.
